ABSTRACT OF THE DISCLOSURE

A bracket assembly for use in elevator systems mountable on a guide rail in an elevator hatchway. The bracket assembly includes a holdown clip means for temporarily retaining the bracket assembly to the guide rail and a J-shaped bolt and cooperating bearing points with means for adjusting the relative spacing therebetween to effect a secure mounting between the guide rail and the bracket assembly in a fixed angular relationship. The bracket may be employed for supporting a switch vane assembly of the leveling mechanism for controlling elevators.

Background of the invention

Field of the invention.—The invention pertains to a bracket assembly for elevator systems which includes means for embracing opposite surfaces of a supporting column to militate against any relative movement therebetween.

Description of the prior art.—Elevator control systems include means which automatically control the final leveling and stopping operation for the elevator car at a variable distance from a floor to be served, which distance is typically determined by the instantaneous velocity at the moment the stopping operation is initiated. In such operation of an elevator, a number of controls is automatically called into action in stopping the elevator car and leveling it with respect to the floor being served. The sequence of control operations, as the car approaches a floor, typically includes first switching the car from the high-speed running condition to a deceleration condition. The deceleration characteristics are adjusted so that the car will be moving at fast-approach speed when it is approximately two feet away from the floor. At this point, one of a plurality of magnetic inductor switches on the elevator car comes opposite to one of a plurality of vertically spaced ferromagnetic vanes mounted in the elevator hatchway to establish the controls in the fast-approach speed. This condition typically holds until the car is a certain distance (the exact distance being varied by adjustment to suit the particular elevator) away from the floor another inductor switch is operated by cooperation with one of the spaced vanes to call for slow-approach speed. The car then decelerates until it is moving slowly so that it is ready to stop the instant the first closed inductor switch leaves the activating vane thus permitting that switch to open. Should the car overrun, another inductor switch (normally operated if the car is approaching from the other direction) is energized to establish a reverse slow-speed approach condition thus bringing the car back to the selected floor. The successful operation of such

2

a control system depends upon the accuracy of operation of the inductor switches which, in turn, depends upon the relative disposition of the switches and the cooperating spaced magnetizable vanes.

Conventionally the ferromagnetic vanes are mounted in vertically spaced relation in the elevator hatchway on the guide rails. In order to properly effect such mounting, the installation is accomplished by a mechanic situated or positioned on the top of an elevator car leveled at the desired floor. One end of the vane bracket is loosely secured to the guide rail by means of a pair of guide rail clamps held in place by respective spaced nut and bolt units, one on one side of the guide rail flange and the other on the other side of the guide rail flange. After the nuts are loosely tightened, the vane assembly is positioned vertically to properly align the vanes on the free end of the vane bracket with the respective leveling inductor switches mounted on the elevator car. The nut and bolt units are then tightened to fixedly position the vane parallel to the guide rail and at a suitable level with respect to the inductor switch assembly. It will be appreciated that the installation of the vanes is rather difficult to accomplish since there is at least one nut and bolt unit on each side of the guide rail which must be tightened simultaneously by the installer who must at the same time, make certain that the vane bracket is properly aligned.

It is an object of the present invention to produce an elevator switch vane bracket assembly which employs only a single adjusting nut means for fixedly securing the assembly to an associated guide rail.

Summary

The objects and advantages of the invention may be achieved by a bracket assembly for securing hardware to a columnar member in an elevator hatchway comprising a main body portion having hardware affixed thereto and containing an aperture; a threaded fastener; a spaced apart bearing point on said body portion for contact with an edge of the columnar member; a J-bolt having a threaded shaft at one end extending through the aperture of the main body portion and for threaded engagement with the threaded fastener and the other end terminating in a J-shape with an opposite edge of the columnar member; at least a pair of shoulders extending from the body portion generally parallel to the axis of the J-bolt for abutting a surface of the columnar member; and a holdown clip extending from the body portion for engagement with an opposite surface of the columnar member cooperating with the shoulders for temporarily retaining the bracket in place on the columnar member until the threaded fastener is tightened.

Brief description of the drawings

Other objects and advantages of the invention will become readily apparent to those skilled in the art from reading the following detailed description of an embodiment of the invention when considered in the light of the accompanying drawings, in which:

FIGURE 1 is a fragmentary top plan view of an elevator hatchway with a car therein disclosing the manner in which the apparatus described and claimed herein is mounted;

FIGURE 2 is an enlarged plan view of the bracket assembly embodying the features of the invention;

FIGURE 3 is an elevational view of the assembly illustrated in FIGURE 2; and

FIGURE 4 is an end view of the assembly illustrated in FIGURES 2 and 3.

Description of preferred embodiment

Referring to FIGURE 1, there is shown an elevator hatchway 10 within which an elevator car 12 is positioned for vertical travel. Typically, guide rails are fixedly mounted on opposite sides of the hatchway 10 for guiding the elevator car 12 during its travel. Since FIGURE 1 is a fragmentary view, only a single guide rail 14 is illustrated. The guide rail 14 includes a pair of oppositely extending flanges 14' and 14". Guide rollers or shoes (not shown) affixed to the elevator car 12 are adapted to ride on respective well-machined faces of the inwardly extending supporting beam portion 16 of the guide rail 14. The cooperation between the guide rail 14 and the guide rollers or shoes militates against any car sway during the operation of the elevator.

The typical elevator car, comprising the flooring, walls and roof is mounted within a car sling which completely encircles the car and provides the supporting structure which is coupled to one end of a supporting cable. The other end of the cable may be carried over a drum at the top of the hatchway, which drum is coupled in a conventional manner to a hoist motor.

The car sling includes horizontally extending crossheads 18, one disposed at the bottom of the car and the other at the top of the car. The opposite ends of the crossheads 18 are attached to side stile members 20 which extend vertically adjacent each side of the car. The crossheads 18 and the side stiles 20 are preferably formed of high-strength metal channel members which may adequately carry the load imposed thereon by the associated car 12.

Rigidly secured to the uppermost crosshead 18, above the car 12 and generally parallel to the roof of the car, is another channel-shaped member 22 at one extremity of which is rigidly connected a suitable switchbox mounting bracket arm 24. The channel-shaped member 22 is fixedly secured to the crosshead 18 as by means of rail clips secured by threaded fasteners 26 which extend through adjusting slots 28 formed in the channel-shaped member 22. The adjusting slots 28 allow for adjustment of the channel-shaped member 22 perpendicularly to the crosshead 18 for the reasons set forth hereinafter. Fixedly secured to the opposite extremity of the switchbox mounting bracket arm 24 from that secured to the channel-shaped member 22 is a leveling switch assembly 30. In the exemplary embodiment the assembly includes three groups of vertically aligned switch units only one of each being shown as 32, 34 and 36 of U-shaped cross sections. In one of the legs of each of the switch units 32, 34 and 36 there is disposed a bar magnet and in the opposite leg in general alignment with the bar magnet is a magnetically actuated reed switch.

Mounted on the associated guide rail 14 at each floor level are stationary vanes 42, 44 and 46 to be aligned with respective vertically aligned series of the switch units 32, 34 and 36. The vanes 42, 44 and 46 are bolted or otherwise suitably affixed to one end of an arm 48 of a bracket assembly of the invention, as illustrated in FIGURES 2, 3 and 4. A generally U-shaped end piece 50 is spot welded, as at 49 on flanges 51 and major face 53, or otherwise affixed to the opposite end of the arm 48. The end piece 50 has two spaced apart upstanding ears 52 and 54, the leading edges 55 of which are adapted to bear against one edge of the flange 14' of the columnar guide rail 14 when in use. In order to assure for the proper alignment of the bracket assembly and the associated hardware, careful consideration must be given to making certain that the line joining the leading edges 55 of the

spaced apart upstanding ears 52 and 54 is perpendicular to the longitudinal center line of the arm 48. Vanes 42, 44 and 46 are provided with a series of keyhole slots (not shown) spaced along their length to accommodate and closely fit screws 57 mounted in tapped apertures 59 in arm 48. Apertures 59 are paired across the width of arm 48 with their center lines perpendicular to the longitudinal center line of arm 48 and thus parallel to the line joining the leading edges of ears 52 and 54. It is important that the vanes 42, 44 and 46 are disposed parallel to the path of travel of the car, as dictated by the guide rails 14. The vanes 42, 44 and 46 must fit in close proximity to their respective switch units 32, 34 and 36 but there can be no physical contact or interference during the relative movement therebetween.

Intermediate the ears 52 and 54, the end piece 50 has an aperture for receiving the threaded shank portion of a J-bolt 56. The threaded shank portion of the J-bolt 56 is adapted to receive a nut 58 and a lockwasher 60. The opposite end of the J-bolt 56 is provided with an upturned hook-like portion 61 adapted to extend through a slot 63 formed generally along the longitudinal center line of the arm 48 and hook around the opposite edge of the flange 14" of the guide rail 14 from the edge bearing against the leading edges 55 of the ears 52 and 54.

A holdown clip 62, which advantageously is integral with the U-shaped end piece 50, is positioned on the end of the arm 48 substantially midway between the ears 52 and 54 of the end piece 50 and has a flat terminal portion 64 spot welded as at 49 or otherwise suitably affixed to the surface 53 of the end of the arm 48. The opposite end of the holdown clip 62 is provided with an upturned lip 66 which facilitates the initial placement of the bracket assembly on an associated guide rail. Tip 66 bears against the face of rail flange 14' which faces the car sling. It is spaced from the face 53 of the arm 48 less than the rail flange thickness to frictionally engage that flange when the bracket is mounted as in FIGURE 1. It will also be noted that the holdown clip 62 is of substantial breadth to adequately provide its hold down function when in use.

In order to insure an accurate positioning of the face 53 of arm 48 parallel to the longitudinal running face of the rail as a reference surface for mounting elements such as leveling vanes having substantial length in that direction, care is exercised in forming the face 53 to insure that spaced regions across its width and throughout its length are in a common plane. In the event there is a deviation in flatness of surface 53 this deviation should be concave with respect to the surface which abuts the rear of the rail flanges whereby at least the portion of the surface 53 adjoining the flanges 51 are coplanar.

With the above description of the structure in mind the appropriate installation procedure will now be described. The switch vane bracket assembly illustrated in FIGURES 2, 3 and 4 is mounted on the guide rail after the car control circuits are operating. The elevator car is initially leveled at a floor and a switch vane bracket assembly is mounted by initially loosening the nut 58 of the J-bolt 56 to allow for enough space between the leading edges 55 of the ears 52 and 54 and the end of the hook-like upturned portion 61 of the J-bolt 56 to accommodate the reception of the flanges 14' and 14" of the guide rail 14. During this procedure the switch vane bracket assembly is rocked to a position to allow the flange 14' of the guide rail 14 to be received between the upturned terminal portion 66 of the holdown clip 62 and the face 53 of bracket arm 48. The spring tension of the holdown clip is sufficient to adequately retain the vertical position of the switch vane bracket assembly until the mechanic tightens the nut 58 to reduce the distance between the bight of upturned edge end 61 of the J-bolt 56 and the leading edges of the cooperating ears 52 and 54 to tightly engage the flanges of the guide rail 14 therebetween. It will be understood that prior to this time the vanes 42, 44 and 46 have been properly bolted to the end of the arm 48 by threaded fasteners 57 shown

in FIGURES 2 and 3. After the switch vane bracket assembly has been suitably located at the desired vertical position, the channel-shaped member 22 is suitably secured to the crosshead member 18 by threaded fasteners 26. Next, the switchbox mounting bracket arm 24 is affixed to the end of the member 22 and the reed leveling switch assembly 30 is secured to the terminal end thereof. The reed leveling switch assembly 30 is then adjusted so that the vanes 42, 44 and 46 are properly aligned midway between the legs of the switch units 32, 34 and 36 respectively.

The above procedure of mounting the vanes 42, 44 and 46 is repeated with respect to each floor stop. It will be understood that since there is only a single reed leveling switch assembly 30 with the switch units 32, 34 and 36 mounted on the elevator car, the installation thereof need only be accomplished once.

Thus, in the case of the utilization of the mounting bracket to precisely position leveling vanes in a hatchway by securing the bracket to a vertical guide rail having a pair of opposed flanges at the back face of the rail and a guiding element extending from between said flanges toward the elevator and longitudinally extending along the path of travel of the elevator, the bracket comprises a channel-shaped arm 48 having a first major face 53 and opposed, longitudinally extending, marginal flanges 51 extending away from the first major face. Secured to the arm 48 for mounting on the guide rail is a U-shaped base 50 having legs 67 secured to the marginal flanges 51 and a bight 68 extending between the flanges 51. The bight has an aperture through which the J-bolt 56 extends. Ears 52 and 54 on each of the legs 67 extend from the legs beyond the first major face 53 and have leading edges 55 generally perpendicular to the face 53 which are aligned across the arm perpendicular to the longitudinal axis of the arm. J-bolt 56 has a shank extending through the bight aperture and extending along the arm 48 between its flanges 51. Nut 58 reacts against the bight 68 to advance the bolt relative to the bight when the nut is rotated. The major face 53 of arm 48 has an elongate aperture 63 in alignment with the bolt shank 56. A clamp element in the form of a bight 61 on the J-bolt secured to the bolt shank and extending through the aperture 63 protrudes beyond the first major face 53 of arm 48 to clamp against one flange of the rail in opposition to the bearing surfaces provided by the leading edges 55 of ears 54 and 52. By this arrangement the bracket arm 48 is assured of being established in a perpendicular orientation relative to the vertical flanges of the elevator guide rail such that the precisely positioned mounting means in the form of bolts 57 at the end of arm 48 remote from the guide rail are aligned in pairs parallel to the guide rail. In such an arrangement the keyhole apertures in the flanges on the leveling vanes, when fitted over the heads of the bolts, cause the leveling vanes to be precisely arranged parallel to the guide rails at a fixed distance from those rails. While the paired mounting means 57 are shown in an alignment which is perpendicular to the longitudinal axis of arm 48, it is to be understood that where the complementary mounting means in the leveling vane flanges are offset with respect to each other, the corresponding offset in the mounting means should be established, the significant orientation being that of the length of the leveling vane which should be parallel to the guide rail.

It will be appreciated that the above described structure provides a simple and expeditious mechanism for securing switch vane bracket assemblies to the guide rails disposed in an elevator hatchway. Only a single nut need be tightened to effect the fixed position of the bracket assembly to an associated guide rail.

In accordance with the provisions of the patent statutes I have explained the principle and mode of operation of my invention and have illustrated and described what I

now consider to represent its best embodiment. However, I desire to have it understood that the invention may be practiced otherwise than as specifically illustrated and described without departing from its spirit or scope.

I claim:

1. A bracket assembly for securing hardware to a columnar member in an elevator hatchway comprising:
  - a main body portion containing an aperture;
  - a threaded fastener adjacent the aperture;
  - spaced apart bearing points affixed to said main body portion for contact with an edge of said columnar member;
  - a J-bolt having a threaded shank at one end thereof for insertion through the aperture of said main body portion for threaded engagement with said threaded fastener and the other end terminating in a J-shape for contact with the opposite edge of said columnar member;
  - a surface extending from said body portion generally parallel to the axis of said J-bolt for abutting a surface of said columnar member and having an elongate aperture parallel to the shank of said J-bolt whereby the J-shaped terminating end of said J-bolt extends through the elongate aperture; and
  - a spring biased holdown clip for engagement with an opposite surface of said columnar member cooperating with said surface of said body portion for temporarily retaining said bracket in place on said columnar member, wherein said holdown clip terminates in a free end portion spaced from said surface a distance less than the spacing between the opposed surfaces of said columnar member.
2. A bracket for securing leveling vanes to an elevator guide rail, said guide rail including a mounting base having opposed flanges and a guiding element extending from between said flanges, said guide rail being mounted along the path of travel of an elevator with its guiding element extending from its mounting base toward the elevator, said bracket comprising:
  - a channel-shaped arm having a first major face and having opposed, longitudinally extending, marginal flanges extending away from said first major face;
  - a U-shaped base having legs secured to said marginal flanges and a bight extending between said flanges;
  - said bight having an aperture;
  - ears on each of said legs extending from said legs beyond said first major face and having leading edges generally perpendicular to said first major face which are aligned across said arm perpendicularly to the longitudinal axis of said arm;
  - a bolt having a shank extending through said bight aperture and extending along said arm between said marginal flanges;
  - a nut reacting against said bight to advance said bolt relative to said bight;
  - said major face of said arm having an elongate aperture in alignment with said bolt shank;
  - a clamp element secured to said bolt shank and extending through said elongate aperture to protrude beyond said first major face of said arm generally normal to said arm; and
  - said clamp element and said leading edges of said ears having a separation spanning said opposed guide rail flanges whereby the advance of said bolt clamps said rail flanges between said element and said leading edges of said ears.
3. A combination according to claim 2 including a pair of leveling vane mountings on said arm spaced from said ears along the length of said arm each mounting being adjacent a marginal flange and said pair being centered on a line perpendicular to the longitudinal axis of said arm.
4. A combination according to claim 2 wherein a leveling vane adapted for mounting on said bracket has a pair

of spaced mounting elements including paired leveling vane mountings on said arm, each adjacent a flanged margin of said arm and oriented to register with the mountings on said vane to maintain said vane parallel to said guide rail.

5. A combination according to claim 2 wherein said base includes a tab extending from said bight along said first major face; and

means securing said tab to said face.

6. A combination according to claim 5 including a 10 spring finger on said tab extending away from said major face of said arm and bent back toward said arm; and a bearing face on said finger between said leading edges of said ears and said clamp element, said bearing face being spaced from said first major face of said 15 arm a distance less than the thickness of said rail flanges and resiliently biased toward said face.
